[57] CLAIM

The ornamental design for a post attachable to the underside of a truck chassis allowing for the securing of a chain to a spare tire, as shown and described.

DESCRIPTION

FIG. 1 is a top, front and side perspective view of the post attachable to the underside of a truck chassis allowing for the securing of a chain to a spare tire embodying the design of the present invention;

FIG. 2 is a front elevational view thereof, the rear being a mirror image of the front shown in FIG. 2;

FIG. 3 is a side elevational view thereof, the side opposite being a mirror image of the side shown in FIG. 3;

FIG. 4 is a top plan view thereof; and,

FIG. 5 is a bottom view thereof.

FIG.1.

FIG. 2.

FIG. 3.

FIG. 4.

FIG. 5.
